UNITED STATES PATENT OFFICE.

WILLIAM E. BEATTY, OF BAYSIDE, NEW YORK, ASSIGNOR TO WESTERN ELECTRIC COMPANY, INCORPORATED, OF NEW YORK, N. Y., A CORPORATION OF NEW YORK.

REPEATING METHOD AND SYSTEM.

Application filed December 11, 1920. Serial No. 429,930.

To all whom it may concern:

Be it known that I, WILLIAM E. BEATTY, a citizen of the United States, residing at Bayside, in the county of Queens, State of New York, have invented certain new and useful Improvements in Repeating Methods and Systems, of which the following is a full, clear, concise, and exact description.

This invention relates to repeating methods and systems in which weak impulses received at a repeating station are to be repeated and sent out upon the line in modified form. Such a repeating system may be inserted in a telephone line, for instance, for repeating telephone currents or ringing currents and in this case it is necessary that the repeater transmit currents in opposite directions over the line to provide for the two-way transmission of signals.

One object of this invention is to provide a two-way repeating system in which the repeating elements employed are of the so-called "push-pull" type in which two repeaters, which may be vacuum tubes, are connected in opposition without the employment of artificial lines. In such an arrangement, certain portions of the input and output circuits of the repeaters are individual to the repeaters while other portions are in common. Such a push-pull arrangement has the characteristic that currents applied to the common portion of the input circuit produce currents in opposite directions in the individual portions of the output circuit, while currents applied to the individual portions of the input circuit may be made to produce currents in the same direction in the individual portions of the output circuit. This characteristic of a push-pull repeater arrangement is therefore, of particular utility in cases where it is desired, in the outgoing line associated with the output circuit of the push-pull repeater to differentiate between effects produced by currents impressed on the individual portions of the input circuit and currents impressed on the common portion of the input circuit.

It is hereinafter described in detail, how this invention may be applied to certain repeating arrangements claimed in the applications of Nicolson, Serial No. 223,221 filed March 18, 1918, and No. 223,222, filed March 18, 1918, for obtaining the above mentioned differentiation in the outgoing

line associated with each repeater. In the Nicolson application, Serial No. 223,221, is described a repeating system in which two vacuum tube repeaters are connected in opposition between two line sections without the intermediary of balancing artificial lines. A rectifier circuit is provided from the output circuit side of each repeater to the input circuit side of the other. The currents to be repeated coming over one of the lines, after passing through the corresponding repeater, are rectified and applied to the other repeater thereby rendering the latter inoperative during the operation of the first mentioned repeater. The first repeater remains in an operating condition so that repeating may take place in the proper direction between line sections. Upon the cessation of the current to be repeated, both repeaters assume their normal operating condition and either repeater is subsequently rendered inoperative by the currents coming in over the other line so that the two-way transmission of signals is provided.

In the Nicolson application, Serial No. 223,222 two repeating arrangements, without the intermediary of balancing networks, are provided by having a generator of alternating current oppositely connected to the two repeater elements so that the repeaters are alternately rendered inoperative at a frequency which is the frequency generated by the generator. One repeater is thus rendered inoperative when the other repeater is rendered operative so that a local circulation of power is prevented. Either repeater, however, is always in condition to repeat the incoming impulses due to the fact that the repeater is rendered inoperative at a high frequency which may be near the upper range of audibility or may be beyond the range of audibility.

In accordance with this invention and as hereinafter more particularly described, each of the two repeaters connected in opposition between the two line sections is of the push-pull type. The currents to be amplified are impressed on the individual portions of the input circuits and the outgoing line is associated with the individual portions of the repeater output circuit. The paralyzing potentials, however, whether due to a generator continuously operated, or due to rectified currents from the output circuit

of the repeater in operation at any particular instant, are preferably applied to the common portions of the input circuit of each push-pull repeater. This arrangement 5 has the advantage that when the paralyzing potential reduces to zero the output current in each portion of the output circuit, the change from a normal value to zero of the current, may be made to produce equal and 10 opposite changes in the current flowing in the outgoing line, thereby obtaining an inoperative condition of each push-pull repeater without producing objectionable potential variations in the outgoing line section. 15 When the repeaters are rendered inoperative at an audible frequency the noises or clicks resulting therefrom would therefore be suppressed by this invention. The objectional potential variations would also 20 be absent in such an arrangement when the output current for each push-pull repeater is changed from zero to its normal value in order to render the repeater operative.

This invention will be better understood 25 by reference to the following detailed description taken in connection with the drawings, in which Fig. 1 represents this invention embodied in a two-way repeater circuit in which a repeater of the push-pull type is 30 employed for repeating in each direction, the repeaters being rendered alternately inoperative by paralyzing potentials applied by a continuously operated alternating current source, and Fig. 2 represents this invention 35 in a similar two-way repeater circuit arrangement except that each repeater is rendered inoperative by rectified currents from the other repeater.

Referring to Fig. 1, the two-way repeating 40 system disclosed therein comprises two line sections 10, 10 and 11, 11 between which are included a push-pull repeater 12 for repeating signaling currents from line section 10 to line section 11 and a push-pull repeater 45 13 for repeating signaling currents from line section 11 to line section 10. The push-pull repeater 12 comprises two vacuum tubes 14 and 15, which contain anodes 16, 17, grids 18, 19, cathodes 20, 21 and auxiliary electrodes 22 and 23 respectively. Grid 18 and cathode 20 are connected to line section 10 by a transformer 25 while the grid 19 and the cathode 21, are connected to line section 50 10 by a similar transformer 26. Each of 55 these transformers is included in one of the individual portions of the input circuit of tubes 14 and 15. The individual portion of the output circuit of tube 14 contains a winding of a transformer 28 while the individual portion of the output circuit for tube 15 contains a winding of a transformer 29. 60 Signaling currents impressed by transformers 25 and 26 upon the grids 18 and 19 will, therefore, produce amplified variations in 65 current through the primary windings of

transformers 28 and 29 in such directions that the E. M. F.'s, induced in line section 11 thereby will be aiding.

The push-pull repeater 13 comprises two vacuum tubes 31 and 32 of the same type 7 as tubes 14 and 15. The individual portions of the input circuits of tubes 31 and 32 are associated with line section 11 by transformers 33 and 34. The common portions of the output circuits of the tubes 31 and 32 are 75 connected to line section 10 by transformers 35 and 36. Signaling currents from line section 11 impressed upon tubes 31 and 32 will produce such currents in the individual portions of the output circuits of the two 80 tubes that aiding E. M. F.'s will be induced thereby in line section 10.

It will be seen that the currents coming in over line section 10 will be amplified by push-pull repeater 12 transferred to line 85 section 11, and unless the means, which will later be described, are provided, the amplified currents in line 2 will also be transferred back by push-pull repeater 13 to line section 10 and push-pull repeater 12 as well. 90 Such a local circulation of power would be objectionable and in order to prevent the same, the following means are provided. Connected between the two auxiliary electrodes 22 and 23 of vacuum tubes 14 and 15 and the two cathodes 20 and 21, is the secondary winding of a transformer 38, the primary winding of which is in circuit with any suitable generator 39 of alternating current. When the generator 39 supplies a 100 wave which makes the auxiliary electrodes 22 and 23 negative with respect to the cathodes 20 and 21, the space current within the tubes 14 and 15 will be reduced substantially to zero and the push-pull repeater 12 will 105 thereby be rendered inoperative. When the generator 39 supplies a wave which makes the auxiliary electrodes 22 and 23 positive with respect to the cathodes, the push-pull repeater 12 is in condition to repeat current 110 from line section 10 to line section 11. The times when the push-pull repeater 12 is inoperative do not interfere with this repeating, since each inoperative period is made 115 of short duration.

Generator 39 is also connected through a transformer 40 to impress alternating currents between the auxiliary electrodes and the cathodes of tubes 31 and 32 in such a manner that push-pull repeater 13 is inoperative at the time push-pull repeater 12 is operative and push-pull repeater 13 is operative at the time push-pull repeater 12 is inoperative. This insures that a local circulation of power between the repeaters will 120 be prevented.

It will be noted that generator 39 is associated with the common branch of the circuit connection between auxiliary electrodes 22 and 23 and their cathodes. The genera- 125

tor 39, therefore, changes the potentials of auxiliary electrodes 22 and 23 in a similar manner so that the space current between anode 16 and cathode 20 will be reduced to zero at the same time the space current between anode 17 and cathode 21 is reduced to zero. Since the output circuit current flows in opposite directions in the primary windings of transformers 28 and 29, it follows that the reduction to zero of the current through these primary windings will produce equal and opposite E. M. F.'s in the secondary windings of the two transformers. Line section 11, therefore, will have no resultant E. M. F. induced in it due to the changes in the space current produced by generator 39 when the tubes are rendered operative or inoperative. The subscriber receiving the messages repeated by push-pull repeater 12 will, therefore, not receive any objectionable potential variations or noises due to the operation of the generator 39.

The two-way repeating system of Fig. 2 is similar to that of Fig. 1, except that different means are provided for preventing the local circulation of power. The output circuits of tubes 50 and 51 are provided with transformers 52 and 53, by means of which some of the amplified currents from tubes 50 and 51 are transferred to a rectifying circuit 54 which impresses the amplified and rectified currents between the filaments and the auxiliary electrodes 55 and 56 of vacuum tubes 57 and 58. The circuit 54 comprises a suitable rectifier such as a vacuum tube rectifier 60 (as shown) and this rectifier is connected in circuit in such a way that electrodes 55 and 56 are made negative with respect to their respective cathodes. The negative potential applied to these two auxiliary electrodes is sufficient to reduce the space current within the tubes 57 and 58 to zero.

Repeater tubes 57 and 58 are consequently rendered inoperative, while the repeater tubes 50 and 51 are transmitting the current to be repeated. In order to release the negative charge on auxiliary electrodes 55 and 56 when current is no longer coming in over line section 61, the rectifier 60 is provided with a leakage path 62. This leakage path, as shown, comprises a core inductance 54 which has a sufficient time lag to maintain the negative potential of the auxiliary electrodes 55 and 56 in spite of variations of the incoming current. Upon a substantial interruption in the incoming line, the potential between the auxiliary electrodes and the cathodes of tubes 57 and 58, is equalized through the leakage path 62.

The repeater tubes 57 and 58 similarly have coupled to their output circuits, a rectifier 65 similar to rectifier 60 by means of which the rectified currents from the output circuits of tubes 57 and 58 may be applied

between the auxiliary electrodes 66 and 67 and their cathodes of tubes 50 and 51. It will be apparent that currents coming in over either line section 61 or 68 will render one of the push-pull repeaters inoperative so that the currents in the outgoing line section cannot be transmitted back through the other push-pull repeater, thereby preventing a local circulation of power.

Inasmuch as the rectifier circuits impress similar potentials upon the two auxiliary electrodes of each push-pull repeater, it follows, as described above in connection with Fig. 1, that equal and opposing E. M. F.'s will be developed in each line section whenever the space current of either push-pull repeater is reduced to zero or restored to normal by the action of the rectifier circuits. No objectionable clicks will, therefore, pass out on the outgoing line section.

It is to be understood that certain aspects of this invention are not limited to two-way repeating systems in which two-way repeater operation is secured without the intermediary of artificial lines or the like, since it is obvious that the push-pull repeater of this invention possesses utility in those types of repeater circuits not employing means for alternately rendering each repeater element inoperative.

It is also to be understood that the circuit arrangements above described may be still further modified without departing in any wise from the spirit of this invention as defined in the appended claims.

What is claimed is:

1. The method of employing a repeater for repeating signals between line sections, which comprises the step of paralyzing said repeater at times and preventing the paralyzation from producing a simultaneous fluctuation in the currents of both of said line sections.

2. The method of employing a repeater for repeating signals between line sections, which comprises the step of reducing the efficiency of said repeater while maintaining fixed the circuit connections therefor, and preventing any simultaneous reaction on both of said line sections due to said reduction.

3. The method of employing a repeater for repeating signals between line sections, which comprises reducing the output circuit current of said repeater to a small value and preventing the simultaneous production of an undesirable reaction on both of said line sections.

4. The method of employing a repeater for repeating signals between line sections, which comprises changing the potential of the control electrode of said repeater to reduce the output circuit current of said repeater below its normal value while preventing the simultaneous production thereby of

1. fluctuations in the currents in both of said line sections.

5. The method of employing a repeater for repeating signals between line sections, which comprises the step of reducing to a small value the energizing current of said repeater while leaving the energization circuit connected to the repeater, while preventing the simultaneous production thereby of fluctuations in the currents in both of said line sections.

6. The method of repeating which comprises repeating in both directions over a line, and preventing a local circulation of power at the repeater by reducing the energizing current therefor to a small value at such times as to permit the normal repeater operation and while preventing the simultaneous production thereby of fluctuations in the currents in both of said line sections.

7. The method of repeating in a signaling system in which are included a line section, a repeater circuit inductively associated with said line section for repeating to a second line section, said circuit having a direct current flowing therethrough, said method comprising changing the value of said direct current and simultaneously neutralizing the effect of said change on both of said line sections.

8. The method of repeating in a signaling system in which are included a line section, a repeater circuit associated with said line section for repeating currents to a second line section, said repeater circuit having at times a direct current flowing therethrough, which method comprises changing the value of said direct current while maintaining fixed the electrical connections for said repeater and neutralizing the effect of said change on both of said line sections.

9. The method of employing a repeater for repeating signals between line sections, which comprises rendering said repeater inoperative at times and subsequently rendering said repeater operative while maintaining fixed the circuit connections therefor and while preventing simultaneous fluctuations therefrom in the currents in both of said line sections.

10. The method of employing a repeater for repeating signals between line sections, which comprises producing a sudden change in the output circuit current of the repeater, and simultaneously neutralizing the effect of said change on both of said line sections.

11. A two way repeating system comprising means for repeating in one direction, means for repeating in the opposite direction, each of said means comprising two repeaters having input and output circuits said input circuits for each of said means having portions in common and other portions individual to each repeater, and voice controlled means for impressing currents

upon the common portion of the input circuits of one of said repeating means.

12. In combination, two line sections, a two way repeating system, therebetween comprising two repeaters having input circuits and output circuits, said input circuits having portions in common and other portions individual to said repeaters, said output circuits having portions in common and other portions individual to said repeaters, means for impressing currents from one of said line sections upon the individual portions of said input circuits and voice controlled means for impressing currents of another type upon said common portion of said input circuits.

13. In combination, two line sections, a two way repeating system therebetween comprising two repeaters having input circuits and output circuits, said input circuits having portions in common and other portions individual to said repeaters, said output circuits having portions in common and other portions individual to said repeaters, means for impressing currents from one of said line sections upon the individual portions of said input circuits, and means associated with the common portion of said input circuits for rendering said repeaters inoperative at times.

14. In combination, two line sections, a two way repeater system therebetween for repeating to one line section signals in substantially the same wave form as received by said other line section, said system comprising two repeaters having input and output circuits, said input circuits having portions in common and other portions individual to said repeaters, and means for impressing a variable potential upon said common portion.

15. In combination, a line, two vacuum tubes having input and output circuits, said input circuits having portions in common and other portions individual to each tube, said output circuits having portions in common and other portions individual to each tube, means for impressing currents to be amplified upon said input circuits, impedance devices in the individual portions of said output circuits for impressing amplified currents upon said line, and voice controlled means for impressing other currents on the common portion of said input circuits.

16. In combination, two line sections, two push-pull repeaters connected in opposite directions between said line sections, each of said repeaters comprising two vacuum tubes having input and output circuits, said input circuits for one of said repeaters having portions in common, and voice controlled means for impressing variable potentials upon said common portion.

17. The combination of two lines, two repeater paths oppositely connected therebe-

tween, impedance varying means responsive to the current impressed on said line for reducing the transmission efficiency of one of said paths, and means for preventing the operation of said means from producing simultaneous current variations in both of said lines.

18. A repeating system comprising two line sections, a two-way repeating means adapted to repeat signals between said line sections, and means for rendering said repeating means inoperative while preventing any substantial simultaneous fluctuations in current in both of said line sections.

19. A repeating system comprising two line sections, a two-way repeating means adapted to repeat signals between said line sections, and means for reducing the efficiency

of said repeating means while maintaining fixed the energization circuits for said repeating means while preventing simultaneous fluctuations in the current in both of said line sections due to said reducing means.

20. A repeating system comprising two line sections, a repeater therebetween having an output circuit, a source of current in said output circuit, and means for reducing at times the current of said output circuit to a low value, while preventing any substantial simultaneous fluctuations in currents in both of said line sections.

In witness whereof, I hereunto subscribe my name this 7th day of December A. D., 1920.

WILLIAM E. BEATTY
